UNITED STATES PATENT OFFICE.

ERNEST HEDENSKOOG, OF MUSKEGON, MICHIGAN.

BALL RACK.

1,418,075.

Specification of Letters Patent. Patented May 30, 1922.

Application filed April 22, 1918. Serial No. 229,901.

To all whom it may concern:

Be it known that I, ERNEST HEDENSKOOG, a citizen of the United States, residing in Muskegon, in the county of Muskegon and State of Michigan, have invented a new and useful Improvement in Ball Racks, of which the following is a specification.

This invention relates in general to ball racks and has more particular reference to ball racks provided for use in connection with pocket billiard tables and the like.

Prior to my invention it has been frequently the custom in playing pocket billiards and other games of like character to remove the balls driven by the several players into the pockets of the pocket billiard table and place them in a rack formed of a plurality of horizontal shelves for the purpose of scoring, each player having a shelf and placing thereon the balls pocketed by him. The use of such a rack as this requires the balls to be lifted out singly and in twos and threes by an attendant or by the players and either carried to the table or deposited in a basket or other receptacle, which operation consumes considerable time and materially delays the play.

It is a principal object of this invention to provide a practical and commercial ball rack from which the balls of the several players may be quickly and directly discharged into the basket or other receptacle for replacement on the table.

I am aware that numerous attempts have been made to construct racks which will automatically deliver the balls but these have proven impractical in use and to be the cause of considerable expense and annoyance. In some instances these racks have required that some of the balls fall considerable distances, ultimately damaging them and in others the arrangement has been such that a discharge of the balls has required the provision of such complicated and easily disarranged relatively moving parts that they were expensive and their periods of use short. Devices of this character are usually used in public billiard rooms where they are subject to rough usage, and considerable abuse, and to be of lasting benefit they must consist of few, simple and readily operated parts.

A further object of the invention is the provision of a device of this character from

which accidental discharge of the balls will be prevented, and where desired to construct the parts of the structure so that any mere meddling will not be likely to result in release.

A still further and important object of the invention is the provision of a rack constructed and arranged to reduce to a minimum the opportunity for the collection of dust and dirt.

A still further object of the invention is the provision of a ball rack having a quick acting discharge and permitting the ready individual removal of the balls as occasion may require.

Another object of the invention is the provision of a ball rack having a quick acting discharge which will not result in materially damaging the pocket billiard balls.

A further object of the invention is the provision of a rack which may be cheaply manufactured, readily operated by unskilled attendants, which will be of pleasing appearance and which will not occupy appreciably more than the space ordinarily allowed for such appliances.

Other objects and advantages of the invention will be apparent as it is better understood from the following description when considered in connection with the accompanying drawing illustrating a preferred embodiment thereof.

On the drawing,

Figure 1 is a front elevation of a ball rack embodying my present invention;

Fig. 2 is a section taken substantially on the line 2—2 of Fig. 1;

Fig. 3 is a section taken substantially on the line 3—3 of Fig. 2;

Fig. 4 is a section taken on the line 4—4 of Fig. 2;

Fig. 5 is a section substantially on the line 5—5 of Fig. 4; and

Fig. 6 is section taken substantially on the line 6—6 of Fig. 5.

The embodiment of my invention shown on the drawing for the purposes of illustration consists of a casing providing for the reception of the balls in vertical columns, each having a lower end closed by movable support which may be retracted to permit the balls in the several columns to drop down into a basket placed just beneath. In order that the basket need not be of the

width of the rack, ways are provided to conduct the balls of the end columns centrally of the rack and into the basket. The columns have open fronts through which individual balls may be inserted and removed, the arrangement permitting any ball of any column to be separately taken out. The casing is preferably inclined slightly as may be seen from viewing Fig. 2,—this is principally for the purpose of permitting the basket to be placed in accurate receiving position beneath the ends of the ball column.

The support for the balls of the several columns in the present instance consists of a narrow movable shelf which is normally held beneath the columns by a spring and adapted to be pushed back out of the way by the pressing of a button extending through the front face of the casing. A lock is provided to prevent the movement of the shelf from beneath the columns except when a basket or other receptacle is in place to receive the balls. This lock is so arranged in the present instance that it is hidden from view and not likely therefore to be operated by anyone casually attempting to manipulate the device.

The embodiment shown on the drawing will now be described in detail. The two side walls 11 have an inclined front edge and a straight vertical rear edge, which rear edges are adapted to rest against the wall of a room when the device is in position for use. The bottom 12 in the present instance consists of a pair of front and rear vertical members 14 and 15 spaced apart a distance slightly greater than the diameter of the balls to be received. The balls are received in the rack in vertical or gravity columns with one ball resting upon another and the bottom ball supported as will be presently described. Guides or partitions 16 extend vertically from just above the bottom 12 to the top 13, said guides providing channels 17 in which the balls may be positioned. The guides 16 are fastened at their tops to a horizontal piece 18 extending between the sides 11 and forming a part of the top and are connected together at their bottoms by a brace 19 and also by being fastened to the front wall 14 of the bottom. The guides or partitions 16 are given a peculiar shape to facilitate insertion and removal of the balls and to insure a retaining of the balls in the columns.

Each guide is recessed as indicated at 21 in Fig. 3, which recesses extend from end to end of the guide. Back of the recesses the material of the guides or partitions extends out as indicated at 22 to present the balls passing out at the back, and at the front projections 23 are provided for similarly holding the balls against movement out of the columns into the front. The projections 23 however, instead of being con-

tinuous as they are at the back are interrupted, as indicated at 24 in Figs. 1 and 2, these interruptions permitting the balls to be inserted and removed from the channels from the front. The projections 23 and the recesses 24 are so arranged that when the balls are in place the largest diameter of the balls will be disposed behind appropriately located projections 23. To take a ball out through the front it is therefore only necessary to lift it until its largest diameter is opposite the interruptions or inwardly extending recesses 24 when it may be taken away. The guides thus provide confining partially arcuate channels in which the balls rest and provide also similar channels arranged at intervals and extending inwardly from the front into communication with the first mentioned channels to permit the balls to be removed. The arrangement of the balls in the channels is indicated in dotted lines at 26 in Figs. 2 and 3.

At the bottom a cross-support or bar 27 is slidably inserted at its ends 28 in grooves 29 extending horizontally in the inner faces of the sides 11 and located just beneath the bottom of the channels in which the gravity columns of balls may be positioned. This bar 27 is provided with a plurality of cushions or rubber bumpers 31 on which the bottommost ball of each gravity column may rest.

A spring 32 embracing a push rod or button 33 secured to the bar 27 is provided to hold the bar in normal position beneath the channels between the partitions 16. This spring is positioned between the bar and a plate 34 secured to the top of the rear wall 15 of the bottom, this wall being cut away at 35 to permit the rod 27 to pass through the plate 34 which forms a bearing for the rod. The rod 33 also has a slide bearing at 36 through the front member 14 of the bottom and carries at its outer end a button 37 which may be pressed by the finger to push the rod and with it the bar 27 back overcoming the action of the springs to release the balls in the gravity column and permit them to roll down into the basket or other receptacle as will be presently explained.

Where desired I provide a device for preventing the balls being released until or except at such times as there is a basket or other proper receptacle ready to receive them when they pass from the channels. This device will now be described and may or may not be provided as the user may desire.

A hook 38 over which the handle of the basket may be engaged may be rigidly connected at 39 upon the under side of the bar 27. The hook 38 is relatively wide and is preferably made of sheet metal. It is provided with a vertically extending slot 41

through which moves a leaf 42 pivoted at 43 on the rod 33 and is pulled to position by the spring 40. When the handle of the basket is engaged over the hook it pushes the leaf from the position shown in solid lines in Fig. 5 to the position shown in dotted lines in the same figure. This leaf constitutes a lock, which when in the position shown in full lines in Fig. 5 engages a notch 44 of a bar 45 as indicated in Fig. 6. The bar 45 is secured against the underside of the centers of the front and back members 14 and 15, which centers are cut away at 46 to receive the handle of the basket. The hook and basket move with the push rod 37 and with the bar 27 and when the leaf 42 is in locking position it prevents this movement by engaging in the slot 44, already described. The hook and lock are positioned beneath the cabinet or rack and are not easily accessible for hand manipulation, therefore there is little tendency on the part of idle observers to toy with the rack when it contains the balls, insuring against an inadvertent release of the balls in the gravity columns when no receptacle is present.

It will be manifest that the hook 38, notched bar 45, leaf 42 and spring 40 may all be omitted if the safety device for preventing improper conscious manipulation be not desired. In this event other support may be provided for the basket or it may simply be held in position by the hand of the operator.

35 The balls move directly out of the columns and down between the bottom members 14 and 15 and into the basket. In order that the rack may be wider than the basket suitable deflecting blocks or inclined channel 40 forming walls 47 are provided at the ends of the space or channel formed between the walls 14 and 15. The position of the partition 16 is best shown in Fig. 2 from which it will be noted that they are inclined somewhat. This inclination permits the balls to roll slightly in moving out of the channels and prevents any tendency to pass out through the recesses 24 when the balls are released.

50 It will be manifest that in a construction of the character described substantially no opportunity is offered for the accumulation of dust and dirt in the channels for receiving the balls, obviating the necessity of 55 brushing out parts of the apparatus and minimizing the soiling of the balls and hands of the players in use.

The center partition, i. e., the one located above the handle of the basket when the 60 basket is positioned, is wider than the others to space the channels or columns apart at this point in order that the balls may not in falling hit the handle and bounce or fall out of the basket. The inner surface of the 65 channel or passage beneath the gravity col-

umns is preferably covered with a layer of felt or cushion material and it will be manifest that the basket, being held in close proximity with all the channels permits the balls to fall therein.

70 It will be manifest that the balls arranged in gravity columns above the basket drop substantially together and in paths individualized to the several columns when the support is removed.

75 In order that the push rod 37 may not be actuated by a person leaning against it or the butt of a cue striking it in the playing upon the billiard or pocket billiard table, I provide a guard or safety device consisting 80 of, in the present instance, a pair of blocks 51 fastened on the outer face of the vertical member 14 and extending out upon opposite sides of the outwardly extending portion of the push rod to a distance equal to 85 or greater than the length of this outwardly extending portion. This guard is particularly desirable where the hook 38 and leaf 42 and co-operating parts are omitted since in that event it acts to prevent inadvertent 90 release of the balls and where such parts are provided it insures against damage to the operating members.

95 It is thought that the invention and many of its attendant advantages will be understood from the foregoing description, and it will be apparent that various changes may be made in the form, construction and arrangement of the parts without departing from the spirit and scope of the invention 100 or sacrificing all of its material advantages, the form hereinbefore described being merely a preferred embodiment thereof.

I claim:

1. A ball rack, comprising a casing providing a plurality of channels in which the balls may repose, a discharging device, a support for a receptacle beneath said device and means comprising a notched locking bar and a pivoted member normally engaged in the notch of said bar and removable therefrom by positioning the receptacle on said support for preventing the operation of said discharging device until arrangement is made for the disposition of the discharged 115 balls.

2. A ball rack, comprising a casing providing a plurality of channels in which the balls may repose, a discharging device, a support for a receptacle beneath said device, and locking means releasable by the receptacle when placed on said support for preventing the release of said discharging device when no receptacle is in position to receive the discharged balls.

3. A ball rack, comprising a casing providing a plurality of ball receiving channels, a support for a basket or other receptacle for receiving the balls from said channel, and means releasable by the basket or other 130

receptacle on said support for producing a discharge of the balls of said channels into said basket or receptacle.

4. A ball rack, comprising a casing providing a plurality of ball receiving channels, a support for a basket or other receptacle for receiving the balls from said channel, a latch releasable by the basket or other receptacle on said support and means normally restrained by said latch for producing a discharge of said balls in said basket or other receptacle on said support.

5. A ball rack, comprising a plurality of gravity column forming members, a collecting runway for receiving the balls forming said gravity columns, means for supporting a basket or other receptacle for receiving the balls from said runway, and means releasable by a basket or other receptacle on said support for supporting said gravity columns of balls.

6. A ball rack, comprising a casing pro-

viding a plurality of channels in which the balls may repose, a discharging device, means locking the discharging device out of action, a receptacle support, said locking means being released by a basket or other receptacle for receiving the balls when the same is placed on said support to permit operation of said discharging device.

7. A ball rack, comprising a plurality of channels for receiving the balls and arranged in gravity columns, a hook therebeneath adapted to support the handle of a basket and locking means releasable by engagement of the basket handle with said hook to provide for the discharge of the balls into said basket.

Signed in the presence of two subscribing witnesses.
